UNITED STATES PATENT OFFICE.

CLINTON L. BOPP, OF WATERLOO, IOWA.

AUTOMATIC TRAIN-STOP AND CAB-SIGNAL.

1,114,438.

Specification of Letters Patent.

Patented Oct. 20, 1914.

Application filed February 24, 1913. Serial No. 750,427.

To all whom it may concern:

Be it known that I, CLINTON L. BOPP, a citizen of the United States, residing at Waterloo, in the county of Blackhawk and State of Iowa, have invented certain new and useful Improvements in Automatic Train-Stops and Cab-Signals; and I do hereby declare the following to be a full, clear, and exact description of the invention, such as will enable others skilled in the art to which it appertains to make and use the same.

This invention relates to cab signal systems, and an object of the invention is to provide circuits which will automatically stop the train under certain conditions.

A further object of the invention is to provide a signal system which will automatically actuate the means for starting the setting of brakes, but which will contain a circuit making it possible to check the setting of the brakes.

A further object of the invention is to provide a locomotive with duplicate circuits and duplicate trip levers one of which may be used when the train is traveling in one direction, and the other of which may be used when the train is traveling in the opposite direction.

With these and other objects in view, the invention consists in certain novel constructions, arrangements and combinations of parts which will be hereinafter fully described, and then specifically pointed out in the claims.

The drawing shows a diagrammatic view of the circuits and part of the structure carried by a locomotive.

The circuits disclosed herein are designed to remain normal when the trip lever engages a "live" or charged rail, and are designed to indicate danger when the rail engaged by the trip lever is "dead" or uncharged.

In order to accomplish the foregoing objects, the locomotive is provided on each side thereof with a bracket 1, to which is pivotally connected a trip lever 2, carrying an arm 3, adapted to be engaged by ramp rails 4 suitably located along the track. The trip lever 2 is further provided with an arm 5 normally held in upright position by means of the spring 6 and also carrying the screw contact 7 adjustably mounted thereon, and insulated therefrom. The bracket 1 carries an insulator to which is suitably secured in

any manner a metallic contact point 8 which is adapted to make connection with the screw 7. One of these trip mechanisms is provided on either side of the locomotive so that the locomotive may be able to run in both directions over a single track having ramp rails on one side only.

Normally, the direct current generator 9 is driven by any suitable means not shown, and feeds current to a brush 10 from where the current passes through wire 11, armature 12, contact 13, electromagnet 14, wire 15, electromagnet 16, wire 17, wire 18, metallic contact point 8, screw 7, wire 19, switch 20, to wire 21, wire 22, wire 23, and back to the generator through the brush 24. Current flowing in this circuit will hold the electromagnets 14 and 16 energized, which will result in the constant attraction of armatures 12, and 25, respectively, it being noted that the maintenance of this circuit is dependent upon the contact between the screw 7, and the metallic strip 8. When the armature 12 is in raised position, as shown in the drawings, current will flow from generator 9, brush 10, wire 11, armature 12, contact 26, wire 27, wire 28, solenoid 29, wire 30, wire 22, wire 23, brush 24, back to the generator 9. Current flowing in this circuit will hold the solenoid 29 normally energized. Slidably mounted within the solenoid 29, is a core or rod 30', the upper end 31 of which is reduced and is adapted to control an air passage 32. The lower end 31 of the core or plunger 30 is provided with a collar and a spring 33, so that as soon as the solenoid 29 is deenergized, the spring 33 will force the plunger downwardly so that the reduced end 31 will open the passage 32. While this circuit is closed, another circuit is closed through the white lamp which is as follows: generator 9, brush 10, wire 11, armature 12, contact 26, wire 34, white lamp 35, wire 36, wire 37, wire 23, and back to the generator 9 through the brush 24. Thus it will be seen that under normal conditions, which means that the contact between screw 7 and contact 8 is closed, the solenoid 29 will be energized and the white light 35 will be burning. Assume now that the locomotive approaches the end of a block, and that the arm 3, engages a "dead" ramp rail 4, the trip lever will be depressed and the connection between the screw 7 and contact point 8 will be open. As will be seen by tracing the first circuit

2

above traced, the breaking of this latter contact will open the circuit through the magnets 14 and 16. As soon as the magnet 14 is deenergized, the armature 12 will drop until the same engages the contact point 36, at which time the following circuit will be completed: generator 9, brush 10, wire 11, armature 12, contact 36, wire 37, red lamp 38, wire 39, wire 37, wire 23, and back to the generator 9 through brush 24. Thus, it will be seen that when the arm 3 of the trip lever engages a ramp rail, the red light 38 will burn. Also, inasmuch as the burning of white light 35 and the continued energization of solenoid 29 depends upon the keeping of contact 26 in engagement with armature 12, it will be seen that both of these devices will be disconnected from the generator 9 when the armature 12 drops to engage contact 36. Therefore, when a "dead" rail is engaged, the white light will be extinguished, the red lamp will be lighted and the plunger 30 will be forced downwardly by spring 33 to open the passage 32.

25 When the passage 32 is opened, air pressure entering pipe 40, as indicated by the arrow, will force the plunger 41 downwardly, but it will be noted that the passage 32 is very much smaller than the bore within which the plunger 41 moves, so that an appreciable time will be required for the descent of said plunger 41. During this time, if the engineer desires to prevent the setting of the brakes, he will push the button 42 which is slidably mounted upon the cab and held normally outward by means of the spring 43. When the button 42 has been pushed in, the contact arm 44 will contact with the contact point 45, at which time the following circuit will be completed: Current will flow from the generator 9, over brush 10, wire 11, wire 46, wire 47, contact arm 44, contact point 45, wire 48, wire 28, solenoid 29, wire 30, wire 22, wire 23, and back to the generator 9 through brush 24. Thus, the pushing of the button 42 will result in the reenergization of the solenoid 29, and if this reenergization has taken place before the plunger 41 has descended to its lower limit, 50 the setting of the brakes will be prevented. It will also be noted that when the button 42 has been pressed, the following circuit will also be closed: Current will flow from generator 9, brush 10, wire 11, wire 46, wire 47, contact arm 44, contact point 45, wire 27, wire 34, white light 35, wire 36, wire 37, wire 23, and back to the generator 9 through the brush 24. Thus, simultaneous with the reenergization of the solenoid 29 and the continued burning of red light 38, the white light 35 is caused to burn so that the burning of the red and white lights together, will indicate "caution." These results will obtain when the arm 3 engages the "dead" rail section 4. However, when the lever 55

engages a rail section 4 which is live, by means of any suitable mechanism which it is not necessary to show in this application, but shown in a number of devices in use at present current will rise from ground to rail 4 and pass over arm 3, over the bracket 1, over wire 49, through the switch 20 to wire 50, solenoid 51, and from wire 52 to the ground. This circuit will energize the electromagnet 51, and result in the attraction of the armature 53. When electromagnet 51 is energized, a local circuit will be closed as follows: Current will flow from generator 9, over brush 10, wire 11, wire 46, armature 53, wire 54, electromagnet 55, wire 56, wire 23, and back to the generator 9, through brush 24. Current flowing in this circuit will energize the electromagnet 55, which will result in the re-attraction of the armature 12. When the armature 12 has been re-attracted, the contacts 13 and 26 will be made so that the conditions of the cab will remain as though normal. As a matter of fact, the time elapsing between the breaking of the connection between screw 7 and the contact point 8, due to the downward swing of the arm 3, and the energization of electromagnet 55 is so slight, that there is practically no movement of the armature 12. Hence, when the arm 3 engages a "live" rail section, the cab circuits will remain undisturbed.

As shown in the drawings, the switch 20 is of a double-throw type, the upper prongs thereof being connected to a trip mechanism 100 located upon the opposite side of the locomotive from that heretofore described, so that when it is desired to use one of these trip mechanisms and throw the other one out of use, it will be merely necessary to 105 throw the switch into correct position.

As shown in the drawings, the double-throw switch is in a position for energizing the cab circuits from the left hand trip lever, but if it be desired to use the right hand 110 trip lever, it will be necessary merely to throw the switch in the opposite direction, when circuits will be completed which will be identical with those already traced. It may be desirable to throw this switch when the train is working on a track where the third rails or ramp rails are located on one side only of the track, or it may be desirable to throw the cab circuits from one of the levers to the other in a system having 115 ramp rails on either side of the track when it is found that one of the trip levers has become accidentally inoperative. Also, when the armature of the electromagnet 16 is unattracted, and the contact arm 44 is touching contact point 45, the contact will be closed until the electromagnet 16 is again energized, at which time the spring will break the contact. While the device for prolonging the setting of the brakes has been 120 125 130

shown as an air valve, with a restricted passage therein, it is to be understood that other devices may be used, such for instance as that disclosed in my Patent 1,085,012.

5 The operation of the air valve in this application is somewhat similar to the operation of the valve shown in my co-pending application No. 727,955. Air pressure coming in through pipe 40 will pass through the 10 dotted bore 100 seen in the sliding portion of the valve and will pass to the chamber 101. The lower piston is larger than the upper piston and the air pressure will be sufficient because of this, to hold the valve in raised 15 position. When the stem 31 is withdrawn from the duct 32, the air which is in the lower larger chamber will escape through pipe 102 and thereby reduce air pressure in the lower larger chamber to such an extent 20 that the pressure acting upon the smaller upper piston 41 will cause the lowering of the sliding portion of the valve, so that communication is established between the air inlet pipe 40 and the pipe 103 which leads 25 to the brakes.

The air valve shown in this application is a minor part of the invention and I do not care to be limited to any particular kind of valve, inasmuch as this feature of the invention is claimed in the above-identified application.

What I claim is:

1. In a locomotive cab signal, a source of current, an air valve requiring time to open 35 the same, a "safety" signal, a "danger" signal, an electro-magnet, an armature adapted to be attracted by said electro-magnet, electro-magnetic means, adapted, when energized, to prevent the opening of said 40 air valve, a contact adjacent said armature adapted to be connected with said armature when the latter is attracted, a circuit including said source, said electro-magnetic means, said "safety" signal, said contact 45 and said armature adapted to be closed when the armature is attracted by the electro-magnet associated therewith, a second contact adjacent said armature adapted to be engaged thereby when the electro-magnet

associated with said armature releases the latter, a circuit including said source, said "danger" signal, said second contact and said armature adapted to be closed when the armature is released, a switch, a circuit including said source, said switch, said electro-magnetic controlling means, said switch adapted to be closed when the armature has been released by the electro-magnet associated therewith to break connection with the first mentioned contact, and means to energize said electro-magnet associated with the armature.

2. In a locomotive cab signal system, a source of current, an air valve requiring time to open the same, electro-magnetic means adapted, when energized, to prevent the opening of said air valve, a "safety" signal, a "danger" signal, an electro-magnet, an armature for said electro-magnet, a contact associated with said armature adapted to be connected with said armature when the latter is attracted by the electro-magnet, a circuit including said source, said electro-magnetic, means associated with the air valve, said "safety" signal, said armature and said contact associated with the armature, a second contact associated with said armature adapted to engage the latter when the same is released by the electro-magnet associated therewith, a circuit including said source, said "danger" signal, means to energize and deenergize the electro-magnet associated with the armature, a switch, a circuit including said source, said switch and said electro-magnetic means controlling the air valve, and another circuit including said source, said switch, and said "safety" signal, said switch adapted to be closed when the armature is released, thereby causing the "safety" and "danger" signals to be actuated simultaneously.

In testimony whereof I affix my signature in presence of two witnesses.

CLINTON L. BOPP.
